United States Patent Office.

CHARLES A. CONDÉ, OF INDIANAPOLIS, INDIANA.

Letters Patent No. 90,427, dated May 25, 1869.

IMPROVEMENT IN GOVERNOR-STOP-VALVES FOR STEAM-ENGINES.

The Schedule referred to in these Letters Patent and making part of the same.

To all whom it may concern:

Be it known that I, CHARLES A. CONDÉ, of Indianapolis, in the county of Marion, and State of Indiana, have invented a new and useful Improvement in Automatic Cut-Off and Governor-Valve; and I do hereby declare that the following is a full, clear, and exact description thereof, which will enable others skilled in the art to make and use the same, reference being had to the accompanying drawings, forming part of this specification.

This invention relates to an improvement in valves for admitting and cutting off to steam-engines, more particularly designed for governor-valves for throttling the steam, and for an automatic stop-valve, to cut off the steam, in case of accident.

The invention consists in a sliding sectional and open cylinder-valve, operating longitudinally in its chamber, in connection with suitable ports in a properly-constructed seat, or chamber, as will be herein-after more fully described.

In the accompanying plate of drawings—

Figure 1 is a section of the valve and globe through the line *x x* of fig. 2.

Figure 2 is a cross-section of fig. 1 through the line *y y*.

Similar letters of reference indicate corresponding parts.

A is the globe, or shell which contains the valve, and which may be directly connected with a governor for which I have applied for Letters Patent, or with other governors.

B is the valve-seat, or cylindrical chamber, in which the valve works.

C is a steam-chamber around the valve-chamber.

D is the valve, which is hollow and open at both ends.

E is the valve-rod.

The steam is admitted to the chamber C, through the branch-opening F, and discharged to engine through the valve and opening G.

The valve D consists of a series of rings, more or

less in number, secured to two or more internal ribs, *h*, with ports or spaces *i* between them, for admitting steam from the chamber C. The spaces, or ports in the valve are marked *i*.

j represents ports, through the cylindrical valve-seat, which correspond, in position and number, with the spaces, or ports in the valve.

As the valve is moved longitudinally in its seat, it will be seen that the steam from the chamber C may be entirely cut off, by its movement in either direction, and that, being surrounded with steam, it is perfectly balanced, and works without pressure to retard its motion.

The rings forming the ports of the valve-chamber, or seat are stayed by two or more ribs on their outer sides.

When the valve-rod is connected with the cross of the governor-balls, the steam is throttled when the balls expand, as the valve is then given a downward movement.

Should the governor-belt break or fly off, or should any other accident happen, causing the governor to stop, the balls would of course drop, which would cut off the steam by the upward movement of the valve, thus forming a perfect automatic "stop."

The advantages of this arrangement over all stop-motions now in use are many, and must be obvious to all.

Having thus described my invention,

I claim as new, and desire to secure by Letters Patent—

The combination and arrangement of the valve-seat B, valve D, and steam-chamber C, with the ports or spaces *i* and *j*, formed by a series of rings, connected together by ribs, substantially as herein shown and described.

CHAS. A. CONDÉ.
